UNITED STATES PATENT OFFICE.

WARREN E. SMITH, OF HAVANA, OHIO.

CUTTING MECHANISM FOR MOWING-MACHINES.

1,364,414.

Specification of Letters Patent.

Patented Jan. 4, 1921.

Application filed August 7, 1919. Serial No. 315,935.

To all whom it may concern:

Be it known that I, WARREN E. SMITH, a citizen of the United States, residing at Havana, in the county of Huron and State 5 of Ohio, have invented certain new and useful Improvements in Cutting Mechanism for Mowing-Machines; and I do declare the following to be a full, clear, and exact description of the invention, such as will enable others skilled in the art to which it 10 appertains to make and use the same.

This invention relates to improvements in harvesters and mowing machines, and it has more particular reference to an improved 15 means for removably securing the blades to the blade bar or sickle bar, so that the blades may be easily taken off for repairing, etc.

The principal object of the invention is to provide a simple and improved method of 20 attaching or detaching the cutter blades, which is easily accomplished and which is particularly adapted for the purpose for which it is designed.

Other objects and advantages of the invention will be apparent during the course 25 of the following description.

In the accompanying drawings forming a part of this specification and in which like numerals are employed to designate like 30 parts throughout the same.

Figure 1 is a plan or top view of a device constructed in accordance with my invention.

Fig. 2 is a sectional view on the line 2—2 35 of Fig. 1.

Fig. 3 is a top or plan view of a portion of a blade bar or sickle bar, the blades being removed.

Fig. 4 is a detached view of one of the 40 blades.

Fig. 5 is a detached view of one of the clamping plates.

In the drawings wherein for the purpose of illustration is shown a preferred form of 45 my invention, the numeral 1 designates a blade bar which is provided on its upper face with projections or upstanding lugs 2, which are preferably cast integral therewith and diamond-shape in configuration as 50 shown.

The cutting blade 3 is provided with an opening 4 therein corresponding in shape to the lug 2, and it is fitted snugly over said lug, the thickness of the lug being less than

the thickness of the blade. A clamping 55 plate or member 5, which is also preferably diamond-shaped and of a greater area or size than the opening 4 in the blade, is employed to securely fasten the blade in position. This plate or member is provided with 60 an aperture 6 adjacent its center, which is square and countersunk as shown. A bolt 7 of any suitable construction but preferably provided with a square head is passed through the apertured plate or clamping 65 member and then through the apertured lug 2 and bar 1 thus holding the plate tightly against the cutting blade when the nut 8 is tightened.

It should be noted that because of the 70 non-circular shape of the opening 4 in the blade and the non-circular shape of the lug 2, the blade will not rotate, and will remain stationary and in proper position at all times.

Although I have shown the parts 2, 4 and 5 as being diamond-shaped, it is to be understood that they will work equally as well if they are made in any other non-circular shape, such as for instance, square or rectangular, etc.

The construction of my device will permit the blades to be readily attached or detached. It is obvious that the blades may be removed by taking the nut off, thus loosening the clamping plate and bolt, which may then be removed.

It is to be understood that the form of my invention herein shown and described is to be taken as a preferred embodiment of 90 the same, and that various changes in the shape, size and arrangement of parts may be resorted to without departing from the spirit of the invention or the scope of the subjoined claim.

Having thus described my invention, what I claim is:

The combination of a blade bar having diamond-shaped projections thereon provided with centrally disposed apertures extending therethrough and through the bar, a plurality of cutting blades arranged in abutting relationship, each blade being provided with a diamond-shaped opening extending therethrough and fitting snugly 100 around one of said projections, each opening being of a length equal to approximately 105 one-half of the width of the blade and its

direction of elongation being parallel with respect to the movement of said bar, each blade being of a thickness greater than the height of the projections, apertured clamping plates of a greater area than said openings and projections, bolts extending through the apertures in the clamping plates and

openings in the projections and bar, nuts on said bolts, and co-acting means between the heads of the bolts and clamping plates to prevent relative rotation of these parts.

In testimony whereof I have hereunto set my hand.

WARREN E. SMITH.
